CLAIM

The ornamental design for a toy for drawing designs, substantially as shown and described.

DESCRIPTION

FIG. 1 is a perspective view of a toy for drawing designs illustrating our new design;

FIG. 2 is a front elevational view thereof;

FIG. 3 is a top plan view thereof;

FIG. 4 is a side elevational view thereof; the opposite side being substantially a mirror image thereof;

FIG. 5 is a rear elevational view thereof; and,

FIG. 6 is a bottom plan view thereof.

FIG. 1

FIG. 2

FIG. 3

FIG. 4

FIG. 5

FIG. 6
